ELECTRIC MOTOR

Joseph R. Corbett, Cincinnati, Ohio

Application December 31, 1953, Serial No. 28,294

Term of patent 14 years

(Cl. D26—5)

To all whom it may concern:

Be it known that I, Joseph R. Corbett, a citizen of the United States, residing at Cincinnati, in the county of Hamilton and State of Ohio, have invented a new, original, and ornamental Design for an Electric Motor, of which the following is a specification, reference being had to the accompanying drawing, forming a part thereof.

Figure 1 is a side elevational view of an electric motor showing my new design.

Figure 2 is an end elevational view thereof.

Figure 3 is an elevational view showing the end of the electric motor opposite to that of Figure 2.

Figure 4 is a perspective view showing a side and the end illustrated in Figure 3.

Figure 5 is a perspective view showing a side of the motor and the end illustrated in Figure 2.

I claim:

The ornamental design for an electric motor, substantially as shown.
